His Attorney.

UNITED STATES PATENT OFFICE.

THEODORE H. EICKHOFF, OF CLEVELAND, OHIO, ASSIGNEE, BY MESNE ASSIGNMENTS,
TO AUTO-ORDNANCE CORPORATION, OF NEW YORK, N. Y., A CORPORATION OF NEW
YORK.

APPARATUS FOR LUBRICATING AMMUNITION.

1,350,645.

Specification of Letters Patent. Patented Aug. 24, 1920.

Application filed November 27, 1917. Serial No. 204,269.

To all whom it may concern:

Be it known that I, THEODORE H. EICKHOFF, a citizen of the United States, and resident of Cleveland, in the county of Cuyahoga and State of Ohio, have invented new and useful Improvements in Apparatus for Lubricating Ammunition, of which the following is a specification.

This invention relates to ordnance, and more particularly to firearms or guns adapted to employ cartridges or other types of ammunition having an outer shell or casing fitting into the firing chamber thereof. The invention is particularly intended to be utilized to introduce a lubricant, such as a powder or a fluid, gaseous or liquid, into the firing chamber or other part of the apparatus for the purpose of lubrication but in many of its aspects it may be utilized for other purposes.

In the use of ordnance of the type employing cartridges or the like it has been found that the friction between the cartridge case and firing chamber gives rise to numerous difficulties. In hand-operated guns this friction seriously interferes with the quick and easy handling or manipulation of the bolt. In rapid-fire and automatic guns the said friction frequently results in the head of a cartridge case being pulled off, leaving the case stuck in the firing chamber, or else results in the mechanism of the gun becoming jammed or otherwise rendered inoperative. Guns of the latter types may be adjusted to exert a large force in extracting cartridge cases but inasmuch as friction between the cartridge cases and the firing chamber is quite variable the action of such guns even when adjusted for excessive friction is very erratic.

While the faulty action above referred to is incident in a greater or lesser degree to guns of all types in which cartridges or the like are employed, it is particularly noticeable in guns of the type in which the residual pressure of the powder gases is utilized in ejecting the empty ammunition case from the firing chamber. An example of the latter type of gun is found in the patent to J. Blish, 1,181,319, granted March 9, 1915. A gun of this type must be adjusted with a fair degree of accuracy to the conditions of operation and if the conditions of operation change the action of the gun is seriously interfered with. The variable friction inci-

dent to unlubricated ammunition renders the operation of such guns very uncertain, and wholly unsatisfactory as is more or less generally known.

It has been proposed to lubricate cartridges at the time of manufacture or before being distributed to the places of use but this practice gives rise to such numerous and serious difficulties that it has never been employed to any appreciable extent, especially for military purposes. Cartridges covered with a lubricant are liable to deterioration, the lubricant is likely to melt or deteriorate in hot weather, the cartridge cases become sticky and gummy, particles of dirt adhere to the cartridge and are carried into the firing chamber, etc. It has also been proposed to lubricate cartridges at the place of firing prior to the insertion of the cartridges into the gun but this has involved considerable time and trouble and has not been done to any appreciable extent except in practice shooting.

The object of the present invention is to overcome the aforesaid difficulties incident to hand-operated rifles, rapid-fire guns, automatic guns and other types of guns and to render the operation of such ordnance smooth and uniform. More particularly my object is to reduce the friction between the contacting surfaces of the ammunition cases and the firing chamber and to maintain this friction substantially uniform. Another object of my invention is to lubricate said contacting surfaces just prior to the time of firing or of inserting the cartridge into the firing chamber.

A further object of my invention is to lubricate the contacting surfaces of the ammunition cases and firing chamber automatically as by utilizing the force of an explosion in the firing chamber for the purpose, and preferably by utilizing the force of an explosion to effect the lubrication and not merely to control an auxiliary source of energy for effecting the lubrication. A still further object of the invention is to lubricate said contacting surfaces directly, as by applying lubricant directly to the firing chamber, and preferably without perforating the firing chamber. Another object is to distribute the lubricant over the said contacting surfaces in an unusually efficient manner and to this end I preferably provide

means for supplying the lubricant in atomized condition.

Still further objects of the invention, as for example attaining a plurality of the 5 aforesaid objects concomitantly, will be apparent from the following detailed description and the accompanying drawings, in which—

Figure 1 is a vertical longitudinal central 10 section of a portion of a rifle comprising one embodiment of my invention, the parts being shown in firing position;

Fig. 2 is a view similar to Fig. 1 but showing the parts in open or loading position;

15 Fig. 3 is a transverse sectional view on line 3—3 of Fig. 2;

Fig. 4 is a longitudinal central section of one means for adjusting the apparatus;

20 Fig. 5 is a transverse section on line 5—5 of Fig. 2;

Fig. 6 is a transverse section on line 6—6 of Fig. 2;

25 Fig. 7 is a side view of the butt of the gun illustrated in Figs. 1 and 2, parts being shown in section; and

Fig. 8 is a transverse sectional view on line 8—8 of Fig. 1.

The particular embodiment of my invention illustrated in the drawings is incorporated in a rifle similar to that now used in the United States Army. In general this rifle comprises a stock 10, a barrel 11, a firing bolt or breech-block 12, a firing chamber 13, a butt 14, a breech-block retainer 15, and in 30 the stock 10 immediately below the firing bolt 12 is disposed a magazine. The gun differs from the regulation Army rifle in that it is rendered automatic according to the invention of J. Blish disclosed in the above 35 mentioned Patent 1,131,319. As described in the said patent the breech-block retainer 15 slides vertically along a guideway which slopes downwardly and rearwardly. When the bolt 12 is in firing position as illustrated 40 in Fig. 1 the block 15 is forced upwardly behind the bolt by means of spring 16. When an explosion takes place in the firing chamber 13 the rearward thrust of the explosion is transmitted through the bolt 12 and 45 block 15 to the guide behind block 15. As explained at length in the said Blish patent, the slope of the guideway for block 15 is such that the block is locked or clamped against the guideway by the high pressure 50 of an explosion in the firing chamber while the block is forced downwardly along the sloping guideway against the action of spring 16 when the pressure of an explosion falls to a predetermined value. When the 55 block is forced downwardly out of the path of the firing bolt the residual pressure in the firing chamber forces the firing bolt rearwardly and ejects the empty shell. Upon the advancement of the firing bolt a new cartridge 60 is fed from the magazine into the fir- 65

ing chamber and when the firing bolt reaches its foremost position the block 15 springs up behind it to lock it in position during firing.

In accordance with certain objects of the present invention I provide means for lubricating the contacting surfaces of the cartridges and firing chamber and the particular means shown comprises a nozzle 17 disposed in the recess immediately in front of the ramp 18' and directly upwardly and forwardly toward the firing chamber 13. Lubricating material of any type which will reduce the friction between said surfaces, such as oil, powdered graphite, or even water, may be projected through the nozzle directly 75 into the firing chamber. However, I preferably employ atomized oil and I preferably atomize and project it into the firing chamber in the manner now to be described.

At a suitable place, preferably within the 80 gun, I provide a lubricant chamber which is arranged to communicate with the nozzle 17. In the drawings I have shown a cylindrical member 25 containing such a chamber 18 in the neck of the butt 14, the chamber 18 communicating with the nozzle 17 through ducts 19, 20, 21, and 22. The duct 19 may either be formed in the stock of the gun or be comprised of a rubber or metal tube connecting with duct 20 as shown in Fig. 8. The duct 20 85 comprises an axial opening in the left hand end of a pin 23 mounted transversely in the stock of the gun. The duct 21 leads from the inner end of duct 20 downwardly through the rear end of the stock, through the cylindrical member 25, and thence into a plug 24. The cylinder 25 is threaded into the rear end of the frame and into the forward end of the cylinder is threaded the plug 24. In the rear end of plug 24 is 90 threaded a smaller screw plug 26. The duct 22 extends through the plugs 24 and 26. Communicating with the duct 21 at a point in the rear of the forward end of duct 22 is a duct 27 (Fig. 2) which extends upwardly 95 to a duct 28 axially disposed in the right hand end of pin 23 (Fig. 8), the duct 28 communicating with a duct 29 extending upwardly to suitable fluid-pressure means. When air is forced along ducts 29, 28, 27, 21, 100 20 and 19 lubricant is drawn through duct 22 from chamber 18 by the aspirating action of the air passing the forward end of duct 22, the lubricant being atomized as it emerges from duct 22 into the current of 105 air in duct 21.

In order to control the quantity of lubricant drawn from chamber 18 I provide a screw 30 (Figs. 2 and 4) for varying the effective cross sectional area of duct 28, the 110 screw 30 being adjustable along an opening 31 extending transversely of duct 28.

The lubricant chamber into which duct 22 extends should be made relatively small so that the rear end of the duct 22 will be sub- 115 120 125 130

merged in the usual positions of the gun and so that the length of the duct 22 will be comparatively short. I therefore make chamber 18 relatively small and provide a relatively large chamber 32 for carrying a reserve supply of lubricant. The chamber 32 is formed in the rear end of the cylindrical member 25 and may be filled through an opening in its rear end which is normally closed by the screw plug 33. The chamber 32 communicates with chamber 18 through ducts 34 disposed on opposite sides of the screw 35 which is employed to secure the butt to the stock. The ducts 34 extend into the upper portions of chambers 18 and 32 so that lubricant may not flow from chamber 18 to chamber 32 in the usual positions of the gun but so that lubricant may flow from chamber 32 to chamber 18 when the gun is pointed downwardly. The duct 22 preferably extends above the level of the lubricant in chamber 18 so that lubricant will not flow from chamber 18 through duct 21 in normal usage of the gun. The extent to which duct 22 extends upwardly may be varied to suit the conditions of usage.

According to the present invention, in certain of its aspects, the force of an explosion is utilized to introduce lubricant to the firing chamber and to this end I preferably employ fluid pressure derived from the force of an explosion in the firing chamber. The best means of which I am at present aware for thus utilizing the pressure in the firing chamber will now be described.

A cylinder and piston are mounted on a fixed portion of the gun and on the reciprocating bolt respectively, the two parts being disposed in alinement and in parallelism with the path of reciprocation of the bolt so that when the piston is reciprocated in the proper direction in the cylinder air is forced through the lubricating means to the firing chamber. In the drawings I have shown the piston 36 mounted in a cylindrical chamber or guard on the bolt 37 and the cylinder 38 mounted at the rear of the gun frame, but the parts may obviously be reversed. The cylinder 38 is surrounded by a casing 39 into which the piston chamber 37 slidably fits. A compression spring 40 is disposed in chambers 37 and 39 around the piston and cylinder so as to urge the bolt 12 into its forward position. The duct 29 communicates with the rear end of cylinder 38 so that air is forced through ducts 29, 28, 27, 21, 20 and 19 when the piston is moved into the cylinder, thereby forcing lubricant from chamber 18 to the firing chamber in the manner hereinbefore described. This action will take place whether the bolt be actuated by hand or by the force of an explosion, but as hereinbefore stated the action is preferably effected automatically by the force of the explosion. And when my invention is em-

bodied in an automatic gun, either of the type herein shown and described or of other type, the lubricant is preferably forced into the firing chamber by the force of the explosion itself rather than by an auxiliary source of energy controlled by the force of the explosion. This is important for the reason that the system is thus rendered more simple and reliable.

Many ways of utilizing the force of an explosion for automatically lubricating the contacting surfaces of a cartridge and firing chamber other than the particular way chosen for the purpose of illustration will occur to those skilled in the art, and I desire broadly to protect the various novel aspects of my invention.

I claim:

1. Apparatus for lubricating the contacting surfaces between the firing chamber of a gun and ammunition supplied thereto, comprising a fluid chamber associated with the gun so that an explosion in the firing chamber creates a pressure in the fluid chamber, and atomizer means actuated by the pressure in the fluid chamber for applying atomized lubricant to one of said surfaces.

2. Apparatus of the character described comprising a firing chamber, a fluid chamber associated with the firing chamber so that an explosion in the firing chamber creates a pressure in the fluid chamber, and atomizer means actuated by the pressure in the fluid chamber for spraying lubricant into the firing chamber.

3. Apparatus of the character described comprising a breech closure, a firing chamber, a lubricant chamber, a duct extending between the two chambers, and means for transferring a portion of the power of an explosion in the firing chamber through said closure to the lubricant chamber to force lubricant through said duct to the firing chamber.

4. Apparatus for lubricating the contacting surfaces between a firing chamber and ammunition supplied thereto, comprising lubricating means including an atomizer for supplying atomized lubricant to one of said contacting surfaces prior to the insertion of the ammunition into the firing chamber, and means actuated by an explosion in the firing chamber for operating the lubricating means.

5. Apparatus of the character described comprising a breech closure, a firing chamber, a lubricant chamber associated with the firing chamber, and fluid pressure means actuated by an explosion in the firing chamber acting through said closure for forcing lubricant to the firing chamber.

6. Apparatus of the character described comprising a firing chamber, holding means reciprocatably mounted behind the firing

- chamber for holding ammunition in the firing chamber, and means actuated by the reciprocatory movement of said means for lubricating the firing chamber.
- 5 7. Apparatus of the character described comprising a firing chamber, a bolt, and means actuated by the retraction of the bolt for lubricating the firing chamber. 70
8. Apparatus of the character described 10 comprising a firing chamber, a bolt, a lubricant chamber, a duct extending between the lubricant chamber and the firing chamber, and fluid-pressure means actuated by retraction of the bolt to force lubricant 75 through said duct into the firing chamber.
9. Apparatus of the character described comprising a bolt, means for automatically retracting the bolt, and means controlled by the retraction of the bolt for lubricating 80 the gun.
10. Apparatus of the character described comprising a firing chamber, a lubricant chamber, a duct extending between the two chambers, holding means movably mounted 85 behind the firing chamber for holding ammunition in the firing chamber, and fluid-pressure means actuated by said holding means for forcing lubricant from the lubricant chamber through said duct to the firing chamber and for atomizing the lubricant in transit to the firing chamber.
11. In a gun having means for lubricating the contacting surfaces between the firing chamber and ammunition supplied thereto, the combination with the breech-block for holding ammunition in the firing chamber, of means for automatically retracting the breech-block upon firing, and fluid-pressure means actuated by the movement of the breech-block for injecting a 95 spray of lubricant into the firing chamber. 100
12. Apparatus of the character described comprising a firing chamber, a bolt for holding ammunition in the firing chamber, means for automatically retracting the bolt upon firing, fluid pressure means actuated by the bolt, a lubricant chamber, a duct extending between the fluid-pressure means and firing chamber and communicating with 110 the lubricant chamber so that lubricant is drawn from the lubricant chamber to the firing chamber when the bolt is retracted.
13. Apparatus of the character described comprising a firing chamber, a bolt for holding ammunition in the firing chamber, means for automatically retracting the bolt upon firing, and means including a piston and cylinder disposed in the rear of the bolt on the bolt and a stationary portion of the 115 gun respectively, for injecting lubricant 120 into the firing chamber upon movement of the bolt.
14. Apparatus of the character described comprising a firing chamber, a bolt, means 125 for automatically retracting the bolt upon 130 firing, a piston on the bolt, a cylinder mounted in the rear of the piston, the piston and cylinder being collinearly disposed along the path of movement of the piston, a lubricant chamber, a duct extending between the cylinder and firing chamber and communicating with the lubricant chamber so that lubricant is drawn from the lubricant chamber to the firing chamber when the piston is reciprocated in the cylinder. 135
15. Apparatus of the character described comprising a stock, a main chamber in the base of the stock, an auxiliary chamber in the neck of the stock, a duct extending between the main chamber and the upper portion of the auxiliary chamber, and means for drawing lubricant from the lower portion of the auxiliary chamber. 140
16. A gun comprising a lubricant chamber, a duct leading from the lubricant chamber, said duct being continuously open, and means for automatically ejecting lubricant through said duct to lubricate a part or parts of the gun. 145
17. A gun comprising a frame member, a bolt member reciprocatably mounted in a longitudinal chamber in said frame member, one of said members having a cylinder extending along said chamber toward the other member, and the other member having a concentric guard and piston respectively extending along said chamber toward said one member, said piston being adapted to move along the inside and said guard along the outside of said cylinder upon the recoil 150 of the bolt member. 155
18. A gun comprising a frame member, a bolt member reciprocatably mounted in a longitudinal chamber in said frame member, one of said members having a cylinder extending along said chamber toward the other member, and the other member having a concentric guard and piston respectively extending along said chamber toward said one member, said piston being adapted to move along the inside and said guard along the outside of said cylinder upon the recoil of the bolt member, and a recoil spring extending around said cylinder and within 160 said guard. 165
19. A gun comprising a frame member, a bolt member reciprocatably mounted in a longitudinal chamber in said frame member, one of said members having a cylinder extending along said chamber toward the other member, and the other member having a concentric guard and piston respectively extending along said chamber toward said one member, said piston being adapted to move along the inside and said guard along the outside of said cylinder upon the recoil of the bolt member, and means controlled by said piston and cylinder for lubricating the gun. 170
20. A gun comprising a firing chamber, 175

an automatic breech closure, a lubricant chamber, and means for absorbing the energy of recoil of said closure, said means being arranged to utilize said energy to 5 transmit lubricant from said lubricant chamber to a working part of the gun.

21. A gun comprising a firing chamber, an automatic breech closure, a lubricant chamber, air compressing means for absorbing 10 the energy of recoil of said closure, and means arranged to utilize said energy to transmit lubricant from said chamber to a working part of the gun.

22. A gun comprising an automatic 15 breech closure and means utilizing a part of the energy of recoil of the breech closure for lubricating a working part of the gun, said means comprising a buffer arranged to stop the rearward movement of the breech 20 closure.

23. A gun comprising an automatic breech closure and pneumatic means for absorbing the excess recoil energy of the closure and utilizing a part of the absorbed 25 energy for supplying oil to the contacting surface between the firing chamber and ammunition.

24. A gun comprising an automatic breech closure and a combined buffer and

lubricator arranged to stop the rearward 30 movement of the closure and thereby transmit lubricant to the firing chamber.

25. A gun comprising a fluid duct, means for producing a flow of fluid through said duct, a lubricant chamber, and a lubricant 35 duct connecting said lubricant chamber with said fluid duct so that said flow of fluid will automatically draw lubricant from said lubricant duct, said fluid duct being directed to a part of the gun thereby to lubricate 40 the part.

26. A gun comprising a fluid duct, means for producing a flow of fluid through said duct, a lubricant chamber, and a lubricant 45 duct having a nozzle projecting into said fluid duct so that said flow of fluid will aspirate lubricant from said lubricant duct, said fluid duct being directed to a part of the gun thereby to lubricate the part.

27. A gun comprising a firing chamber, 50 a ramp beneath the mouth of the firing chamber, and a fluid duct extending through said ramp to deliver fluid in the region of said mouth.

Signed by me at Boston, Massachusetts, 55 this 16th day of November, 1917.

THEO. H. EICKHOFF.
